THE MINE & SMELTER SUPPLY CO. OF NEW YORK, N. Y., A CORPORATION OF
COLORADO.

ORE-CONCENTRATOR.

1,180,210.

Specification of Letters Patent.

Patented Apr. 18, 1916.

Application filed May 29, 1914. Serial No. 841,877.

To all whom it may concern:

Be it known that we, CHARLES E. THOMPSON and HANS NELSON, citizens of the United States, residing in the city and county of Denver and State of Colorado, have invented certain new and useful Improvements in Ore-Concentrators, of which the following is a specification.

Our invention relates to an improvement in ore concentrators, and more particularly to what is generally known as a sand-table of the well-known Wilfley type.

The primary object of our present invention is to provide a table of greatly increased capacity while maintaining the highest efficiency in saving values.

It consists of a table, the major portion of the surface of which is rifled, these rifles varying in construction and arrangement in different areas or fields of the table surface, these variations being the means of attaining the results mentioned, namely of producing a table of this type of maximum capacity and efficiency.

25 In the accompanying drawings:—Figure 1 is a top plan view of the table; Fig. 2 is a sectional view on the line G—G at the concentrates discharge end of the table; Fig. 3 is a section on a line II—II extending diagonally across the table from the corner or juncture between the concentrates discharge end and the tailings discharge side of the table; Fig. 4 is a section on the line L—I₁ taken lengthwise of the table and at 30 the lower ends of one set of the diagonally-placed rifles; Fig. 5 is a section on the line J—J at the mechanism end of the table; Fig. 6 is a section on the line K—K at the concentrates discharge corner of the table; Figs. 7, 8, 9 and 10 are views in side elevation of rifles on the various planes or fields of the table; Fig. 11 is an illustration of a form the rifles which gradually reduce in height throughout their length might take 35 in lieu of the uniform gradual taper illustrated in the other figures; and Fig. 12 is a transverse section showing rifle-cleats in groups of rifles of uniform height.

As it is well known that tables of this 40 type have a side slope, an adjustment both sidewise and endwise, side wash and endwise motion, these features will not require detailed illustration or elaboration.

The major portion of the surface illustrated is rifled in three main fields or areas, 45 which are designated by the letters A, B and C. Then there are the fields of less area D and E at the concentrates discharge corner and the tailings discharge side of the table respectively, and the remaining relatively smooth field F at the feed corner. The rifles in the two fields A and B, instead of being placed parallel with the tailings discharge side and stroke line of the table, are disposed diagonally to that side 50 and the stroke line. The rifles 1, 1, in the field A, extend from the mechanism end to the diagonal line α , their head terminals starting preferably at or near the corner of the table between said end and the tailings discharge side thence partway across the table toward the feed side, and the rifles 2, 2, in the field B extend from the above-mentioned corner of the table and the upper limits of the field E at the tailings discharge side, to said diagonal line α . These rifles 1, 1, and 2, 2, in the fields A and B 55 preferably are all parallel with each other and tapering gradually and uniformly throughout their entire lengths, being highest at the mechanism end and at the upper limits of the field E near the tailings discharge side and lowest at the diagonal line α , and of gradually and uniformly reduced height from the feed side or rifle β to the 60 juncture of field B with the fields D and E, as the sections shown in Figs. 3, 4 and 5 indicate. This gradual reduction in the height of the rifle-cleats upon the incline of the fields A, B, facilitates rapid removal of the 65 light sand or waste, allowing it to travel diagonally down the incline and over the field E into the tailings race beneath. Each of these individual rifle-cleats instead of being uniformly reduced in height (as shown 70 in Figs. 7 and 8) might be reduced in steps (as shown in Fig. 11), in which event the ends of the steps of each lower rifle would advance slightly beyond the corresponding end of the step of the rifle just above, so 75 that in other words these steps would advance diagonally along the table surface, as is well understood. The higher rifles with the deeper intervening channels toward the feed side of the table, at once catch by far 80 the larger percentage of the heavier concentrates and convey them toward the diagonal line α , and the shallowing channels becoming uniformly shallower and shallower 85 down the slope of the table as the pulps 90

110

level down this inclined surface, are adequate to catch and advance the progressively decreasing percentage of concentrates, and preclude the possibility of their loss while the waste sands meet with less and less resistance by reason of the shallowing of the intervening channels produced by the diminishing height of the riffle cleats, as indicated. The shallowing or shoaling of the channels 5 down the incline of the table, while illustrated as being uniform from riffle-cleat to riffle-cleat, obviously might be arranged in groups of two or more riffles producing groups of channels of uniform dimensions 10 down the incline of the table, while illustrated as being uniform from riffle-cleat to riffle-cleat, obviously might be arranged in groups of two or more riffles producing groups of channels of uniform dimensions 15 each group as shown in Fig. 12.

The riffle-cleats 3, 3, in the field C extend from the diagonal line α to the concentrates discharge end with the exception of three or four at the feed side which terminate one 20 beyond another, and are of uniform height from the diagonal line α throughout the length of each riffle, but the height of the riffles is not the same, they being gradually reduced from the feed side toward the tailings discharge side (as shown in Fig. 2 which is a section taken on the line G—G of Fig. 1) and these are arranged as continuations of riffles in the fields A and B, only at a different angle, preferably extending 25 parallel to the line of stroke and the tailings discharge side as illustrated. There may be one of these riffles 3, 3, for each of the riffles in fields A and B; or one for every alternate riffle in fields A and B; or 30 they may be extensions of every third, fourth, etc., riffles of said fields; or of corresponding groups of riffles as described; or they might be omitted altogether, as these riffles 3, 3, in the field C have little, in fact 35 practically nothing, to do with the concentration or cleaning up, as these riffle-cleats and the intervening channels serve as conveyers of the product, which in the proper normal operative adjustment of the table 40 is commercially cleaned when it has reached the diagonal line α , where substantially the line of separation between the values and waste is maintained.

The higher riffle-cleats on field C nearest 45 the upper or wash-water side of the table forming the deeper and more capacious channels, guide, direct and carry into the concentrates-box the major portion (the heavier) of the concentrates high up on the 50 concentrate discharge end of the table, while the lighter concentrates are carried off by the shallower channels farther down the incline of that field. Obviously the concentrates discharged upon this field C, by the 55 channels in the fields A and B, becoming less and less in quantity as the material under treatment proceeds down the incline of the table, the gradually diminishing channels in the field C have adequate capacity to 60 convey the same, while the uniform shoal-

ing of these channels in conformity with the lowering of the terminals of the cleats of the fields A and B along the diagonal line α preserves a uniformity of the plane of the lands or tops of the entire riffle system of the whole table-surface, for the uniform and even flow of the feed and wash-water, all of which, of course, has to flow transversely across the riffle-cleats. 70

It will be observed that the riffle-cleats in the fields A and B, by reason of their being disposed diagonally to the stroke line of motion and the table being operated with a transverse inclination, and substantially level lengthwise (although not necessarily 75 so) the concentrates caught in the channels of these fields A and B are compelled by the riffle-cleats to climb slightly up-grade, up the transverse incline of the table. This upward climb has the effect of retarding 80 somewhat the advance of the concentrates in these channels, and to subject them for a somewhat longer period of time to the side-wash of the water to thus more completely remove the gangue. 85

The riffle-cleats of the field E, of which four are shown in the drawings, but which it is understood might be more or less in number, preferably extend throughout the length of the table, that is from the mechanism to the concentrates discharge end, and serve to catch particles of value which occasionally find their way entirely across the fields A and B, and to advance them directly on to the field D at the lower concentrates corner of the table, where occurs the final clean-up of the middlings which are gathered there from the fields A, B and E. These riffle-cleats in the field E gradually diminish in height from the mechanism 90 end to the concentrates discharge end of the table, the lowest or last one on the tailings-discharge side preferably being higher for a portion of its length at the concentrates discharge end of the table, and capable of variations as to such height as may 95 best suit for the particular material under treatment. This is done for the purpose of carrying a middling product over the concentrates-discharge end that would otherwise 100 pass over the tailings discharge side from the field D. The building up to suitable height of the lowest riffle-cleat in the field E, which extends through the field D for a 105 suitable distance back from the lower concentrates corner, is of great importance in making a final clean-up of the middlings 110 assembled on the field D, as indicated. 115

The several elevated cleats 6, 6, abutting on the upper side of the feed corner of the field E, six of which are illustrated, but any 120 number of which might be employed, are approximately a foot in length in the full-size table, and from one-half to three-fourths of an inch in height, of such 125 130

other height or length as may be desired for the particular work to be done. These are placed approximately at right-angles to the line of stroke. These cleats are not riffles in the full sense, but may be termed "feed-diverters or distributors," they holding the feed from the feed-box back toward the mechanism end of the table and serving to more equally distribute the silica-bed in its 5 travel to and upon the riffled field A. These feed diverters or distributors 6, 6, assist very materially in adding to the capacity of the table by diverting a large part of the silica toward the portion of the field A abutting 10 upon the mechanism end of the table.

When the pulp is dropped from the feed-box into the intervening space, a partial stratification takes place at this point while passing downward to their lowest ends, 15 whereupon the heavier materials at once start off toward the field C on the relatively smooth surface above the field A, while the lighter are carried downward, impelled by the feed and wash water into the riffles 1, 1, 20 of the field A.

In the most effective operation of this construction, the transverse inclination should be such as to elevate the tops or lands of the riffle-cleats at point *d* on the diagonal line *a* 30 above the horizontal plane level of the same riffle at point *b*, the mechanism end of the table, thus adjusting the plane of the tops or lands of the series of cleats in the fields A and B so as to slope somewhat toward the 35 mechanism end, thus forcing the waste sand back toward the lower mechanism corner, while the concentrates in the intervening channels are impelled toward the field C, slightly up-grade to the diagonal line *a*.

40 The degree of transverse inclination in conjunction and co-operation with the angular disposition of the cleats in the fields A and B to the stroke line of the table has been found to be most effective in increasing the 45 capacity of the table. Increasing the inclination increases the flow and spreading of the waste sands toward the mechanism end of the table.

We claim:—

50 1. A reciprocating concentrating table having a plurality of tapering riffles on the surface which intersect the line of movement of the table, and which terminate along a line at an angle to the line of movement, 55 and riffles of uniform height extending from terminals of certain of the first-named riffles to the concentrates end of the table, and said riffles of uniform height being of decreased height as they approach the tailings discharge 60 side of the table and less in number than the diagonally-placed riffles.

65 2. A reciprocating concentrating table provided with two main sets of riffles, one set tapering and disposed diagonally on the table surface, and of decreasing height suc-

cessively down the surface of the table, and the other set disposed longitudinally and located nearer the concentrates discharge end than, and in an end to end relation with, those of the first set, and the individual 70 riffles thereof uniform in height throughout their length and decreasing in height successively down the slope of the table.

3. A reciprocating concentrating table having three main areas, one comparatively 75 narrow located at the lower tailings discharge side on which surface is a series of longitudinal riffles, another at the concentrates end extending to a diagonal line part way to the feed end on which are longitudinal 80 riffles parallel with those at the tailings discharge side, and the third area having riffles which are arranged diagonally and extend from the feed end and from the highest riffle of the area near the tailings discharge 85 side to the diagonal line.

4. A reciprocating concentrating table having three main areas, one comparatively narrow located at the lower tailings discharge side on which surface is a series of 90 longitudinal riffles, another at the concentrates end extending to a diagonal line part way to the feed end on which are longitudinal 95 riffles parallel with those at the tailings discharge side, and the third area having riffles which are arranged diagonally and extend from the feed end and from the highest riffle of the area near the tailings discharge side to the diagonal line, said diagonal riffles all tapering throughout the length of each 100 and of reduced height from upper to lower side.

5. A reciprocating concentrating table having three main areas, one comparatively 105 narrow located at the lower tailings discharge side on which surface is a series of longitudinal riffles, another at the concentrates end extending to a diagonal line part way to the feed end on which are longitudinal 110 riffles parallel with those at the tailings discharge side, and the third area having riffles which are arranged diagonally and extend from the feed end and from the highest riffle of the area near the tailings discharge 115 side to the diagonal line, said diagonal riffles all tapering throughout the length of each 120 and of reduced height from upper to lower side, the longitudinal riffles at the tailings discharge side tapering throughout, and the riffles at the concentrates discharge end each of uniform height throughout, but each successive one lower than the next rifle above.

6. A reciprocating concentrating table, the major portion of whose surface is riffled, the 125 riffles along the tailings discharge side and the riffles from a diagonal line across the table to the concentrates discharge end approximately parallel with each other and with the line of motion of the table, and the 130

intermediate riffles between said diagonal line and the riffles along the tailings discharge side of the table extending diagonally.

5 7. A reciprocating concentrating table, the major portion of whose surface is rifled, the riffles along the tailings discharge side and the riffles from a diagonal line across the table to the concentrates discharge end approximately parallel with each other and with the line of motion of the table, and the intermediate riffles between said diagonal line and the riffles along the tailings discharge side of the table extending diagonally, said diagonal riffles varying in height throughout their length.

8. A reciprocating concentrating table, the major portion of whose surface is rifled, the riffles along the tailings discharge side and the riffles from a diagonal line across the table to the concentrates discharge end approximately parallel with each other and with the line of motion of the table, and the intermediate riffles between said diagonal line and the riffles along the tailings discharge side of the table extending diagonally, said diagonal riffles varying in height throughout their length, and successive riffles of diminished height from the feed to-

30 ward the tailings discharge side of the table.
9. A longitudinally reciprocating concentrator table, the surface of which has two main sets of riffles, one of which extends parallel with the line of motion of the table, 35 and the other diagonally, the former set of riffles extending from the concentrates discharge end to a line extending diagonally across the table part way to the angle formed between the concentrates discharge 40 end and the tailings discharge side, over said line in proximity to said angle of the table, and thence along the tailings discharge side, and the other set covering the major part of the remaining portion of the 45 table unoccupied by the first mentioned set of riffles.

10. A longitudinally reciprocating concentrator table, the surface of which has two main sets of riffles, one of which extends 50 parallel with the line of motion of the table, and the other diagonally, the former set of riffles extending from the concentrates discharge end to a line extending diagonally across the table part way to the angle 55 formed between the concentrates discharge end and the tailings discharge side, over said line in proximity to said angle of the table, and thence along the tailings discharge side, and the other set covering the

major part of the remaining portion of the 60 table unoccupied by the longitudinal riffles, said riffles at the concentrates discharge end each of uniform height throughout its length, and those at the tailings discharge side of reducing height throughout their 65 length.

11. A longitudinally reciprocating concentrator table, the surface of which has two main sets of riffles, one of which extends parallel with the line of motion of the table, 70 and the other diagonally, the former set of riffles extending from the concentrates discharge end to a line extending diagonally across the table part way to the angle formed between the concentrates discharge 75 end and the tailings discharge side, over said line in proximity to said angle of the table, and thence along the tailings discharge side, and the other set covering the major part of the remaining portion of the 80 table unoccupied by the longitudinal riffles, said riffles at the concentrates discharge end each of uniform height throughout its length, and those at the tailings discharge 85 side of reducing height throughout their length, and the lowermost of which latter riffles are of greater height than its adjacent riffles.

12. A longitudinally reciprocating concentrator table, the surface of which has 90 two main sets of riffles, one of which extends parallel with the line of motion of the table, and the other diagonally, the former set of riffles extending from the concentrates discharge end to a line extending 95 diagonally across the table part way to the angle formed between the concentrates discharge end and the tailings discharge side, over said line in proximity to said angle of the table, and thence along the tailings discharge 100 side, and the other set covering the major part of the remaining portion of the table unoccupied by the longitudinal riffles, said riffles at the concentrates discharge end each of uniform height throughout its 105 length, and those at the tailings discharge side of reducing height throughout their length, said riffles at the concentrates discharge end of varying height from the feed to the concentrates discharge end of the 110 table.
